US0D1070816S

(12) **United States Design Patent** (10) **Patent No.:** **US D1,070,816 S**
(45) **Date of Patent:** **** Apr. 15, 2025**

(54) **TIP FOR AN EARBUD**

(71) Applicant: **Anker Innovations Technology Co., Ltd.**, Changsha (CN)

(72) Inventors: **Fan Zhou**, Shenzhen (CN); **Jingxuan Wei**, Shenzhen (CN); **Zheng Wei**, Shenzhen (CN); **Guoming Song**, Shenzhen (CN); **Qiang Ma**, Shenzhen (CN)

(73) Assignee: **Anker Innovations Technology Co., Ltd.**, Changsha (CN)

(**) Term: **15 Years**

(21) Appl. No.: **29/881,057**

(22) Filed: **Dec. 27, 2022**

(30) **Foreign Application Priority Data**

Jun. 30, 2022 (CN) 202230411735.9

(51) **LOC (15) Cl.** **14-01**

(52) **U.S. Cl.**

USPC **D14/223**

(58) **Field of Classification Search**

USPC D14/205, 223; D24/106, 224; D9/439;

181/135; 381/380-381, 328, 322;

128/864-866

CPC H04R 25/00; H04R 25/02; H04R 1/10;

H04R 1/1016; H04R 1/1058; A61F 11/08

(57) **CLAIM**

The ornamental design for a tip for an earbud as shown and described.

DESCRIPTION

FIG. 1 is a front top perspective view of a tip for an earbud showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines depicting the remainder of the tip for an earbud form no part of the claimed design.

1 Claim, 7 Drawing Sheets
